UNITED STATES PATENT OFFICE.

HERMAN KEENGOOD, OF BALTIMORE, MARYLAND, ASSIGNOR TO ALMA MANUFACTURING COMPANY OF BALTIMORE CITY, OF BALTIMORE, MARYLAND, A CORPORATION OF MARYLAND.

SLIDING-TONGUE BUCKLE.

1,049,732.

Specification of Letters Patent.

Patented Jan. 7, 1913.

Application filed May 10, 1912. Serial No. 898,417.

To all whom it may concern:

Be it known that I, HERMAN KEENGOOD, a citizen of the United States, residing at Baltimore, in the State of Maryland, have invented a certain new and useful Improvement in Sliding-Tongue Buckles, of which the following is a full, clear, and exact description.

The object of this invention is to provide a flat and inconspicuous sliding tongue buckle, for use on trousers and other articles, where it is desirable that the connected strap ends should lie as flat as possible.

It is essential in this class of buckles that the grip of the sliding tongue should be sufficiently strong to hold the thinnest possible strap; and as this gripping action is effected by the draft of the strap on the tongue drawing it into forcible contact with an adjacent end bar of the frame, obviously it is necessary that the relations of the adjacent gripping edges of the tongue and frame should be so intimate as to grip the strap end against peradventure of its slipping. Buckles of this type are made of metal, highly polished, and it is advisable, if not necessary, to interpose some obstacle in the path of the gripping end, either on the frame or on the slide, that will throw the strap out of level or put a bight or crimp in it. Heretofore such obstacles have been in the form of lugs or teeth, but in many instances it would be plainly harmful to expose the strap to any penetration by the teeth. Any obstacle that would put the strap out of plane, and not penetrate it, would be the ideal one. Tests indicate that the desired results are attained by using a sliding tongue having a gripping end bar ridged fore and aft and having these ridges set back from the leading end of the end bar or, in other words, recessing this end bar in front of the ridges thus leaving the leading end projecting beyond and in advance of the ridges, so that such leading end may pass or tend to pass underneath the cooperating end-bar of the frame in gripping the strap, while the ridges serve to crimp the strap without penetrating it, and thus become obstacles to the slipping of the strap when once gripped.

The invention consists of a sliding tongue buckle constructed and operating in accord-

ance with the last described tested buckle, all substantially as I will proceed now to 55 explain and finally claim.

In the accompanying drawings illustrating the invention, in the several figures of which like parts are similarly designated, Figure 1 is a perspective view of one form 60 of buckle, showing the tongue in its foremost position. Fig. 2 is a perspective view of the parts of the buckle detached. Fig. 3 is a top plan view with the sliding tongue moved back to the cross-bar of the frame, 65 and Fig. 4 is a bottom plan view with the parts in the same position. Fig. 5 is a transverse section taken in the slot of the sliding tongue. Fig. 6 is a longitudinal section on a larger scale with the strap ends in gripped 70 position. Fig. 7 is a longitudinal section of the buckle as shown in Fig. 1.

The buckle frame 1 may be, and is here shown as composed of side bars 2, a front end bar 3, a rear end bar 4, all in the same 75 plane, and a cross-bar 5 depressed below the level of the top of the side and end bars. The side bars are provided with depending and introverted flanges 6 to form supporting guideways for the sliding tongue 7; these 80 supporting guideways serving to support the tongue for movement longitudinally of the frame and holding it against escape faceward or backward. The sliding tongue has the end bar 8 with the depending fin 85 -hold 9 on its inner edge. Another end bar 10 is connected with the end bar 8 by the side bars 11, and these side bars are extended at 12 beyond the end bar 10 so as to elongate the side bearings and prevent the 90 tilting of the tongue in the frame. Between these end bars is an opening for the passage of the free end of the strap to be fastened. The end bar 10 is provided with any number of ridges 13 running fore and aft, and 95 upstanding sufficiently to serve as stops to arrest the forward movement of the sliding tongue, and hence prevent its escape from the frame when once in position. The rearward escape of the tongue from the frame is 100 prevented by the contact of the end bar 10 with the depressed sides of the depressed cross-bar 5. By these means after the sliding tongue is once in place, it is held from escape in any direction from the frame. 105 The tongue may be inserted in the frame in

the first instance in a number of different ways, but preferably by springing it into place within the supporting guideways or introverted flanges.

5 It will be observed that the ridges 13 fall short of the forward or leading end of the end bar 10 on which they are made, or, in other words, this leading end is recessed in front of the ridges, and this then leaves portions of this end bar extending forwardly 10 beyond the ridges so that if the buckle be used upon a thin strap, this forwardly extending portion of the leading end of the end bar 10 of the sliding tongue will have a tendency to crowd or bend the thin material underneath the adjacent edge of the front end bar 3 of the frame and render the ridges doubly efficient in gripping the fabric between themselves, their supporting bar and 15 the adjacent edge of the front end bar 3 of the frame.

As already indicated, the upstanding ridges are interposed as obstacles to the escape of the strap end 14 when once it is engaged 20 between the sliding tongue and the adjacent frame, and they thus operate by virtue of the fact that they put as many crimps in the strap as there are ridges. Ordinarily two parallel ridges are sufficient.

30 The supporting grooves or guideways formed by the introverted flanges on the side bars of the frame are of a width to take easily the side bars of the tongue, and so as to permit the tongue to move therein lengthwise without cramping. The flat straight 35 edged character of the sides of the tongue peculiarly fits the tongue for free movement in said grooves or guideways.

The depression of the cross-bar 5 permits, 40 as it were, of the countersinking of the looped end of the strap 15 within the dimen-

sions of the buckle, so as to avoid any undue humping of the fastened end 14.

By the construction described a very slim 45 buckle is produced without in the least impairing its efficiency as a gripping or buckling agent, and moreover the buckle may be economically constructed and assembled.

What I claim is:—

1. A sliding tongue buckle, comprising a 50 frame, and a sliding tongue supported therein, said sliding tongue having a strap-gripping end bar provided with upstanding ridges running fore and aft and said end bar recessed in front of the ridges and thus 55 leaving the leading end of the end bar extending forwardly of the ridges, and said ridges and the forwardly extended end bar coöperating with the frame to crimp the strap and grip it between the tongue and 60 frame.

2. A sliding tongue buckle, having a frame with a front end bar, a sliding tongue supported in said frame and having an end bar provided with fore and aft upstanding 65 ridges, said end bar recessed in front of said ridges so as to leave its leading end extending forwardly beyond said ridges toward the front end bar of the frame, the tongue being supported in the frame below the level of 70 the frame's front end bar, so that the forwardly extended leading end of the end bar of the sliding tongue is adapted to crowd a thin strap end against and under the adjacent front end bar of the frame while its 75 ridges put crimps in said strap end.

In testimony whereof I have hereunto set my hand this ninth day of May, A. D. 1912.

HERMAN KERNGOOD.
